(57) CLAIM

The ornamental design for a front panel of a beverage dispenser, as shown and described.

DESCRIPTION

FIG. 1 is a front view of my new invention; and,

FIG. 2 is a right side view thereof, a left side view being a mirror image thereof.

The surface ornamentation depicted in broken lines in FIG. 1 is shown for illustrative purposes only and forms no part of the claimed design.

1 Claim, 1 Drawing Sheet
